UNITED STATES PATENT OFFICE.

GEORGE W. SLYTER, OF TACOMA, WASHINGTON.

RECLINING-CHAIR.

1,233,927.

Specification of Letters Patent.

Patented July 17, 1917.

Application filed February 9, 1916. Serial No. 77,327.

To all whom it may concern:

Be it known that I, GEORGE W. SLYTER, a citizen of the United States, and resident of the city of Tacoma, county of Pierce, 5 State of Washington, have invented certain new and useful Improvements in Reclining-Chairs, of which the following is a specification.

My invention relates to chairs, and particularly to chairs having a hinged or reclining back, and consists of improvements in the means employed for operating and controlling the hinged back, and for operating other parts of the chair.

One object of my invention is to provide 15 means for operating and controlling the hinged back of such a chair, which means has been hidden from sight, is simple in character and effective to secure the desired 20 result.

Further object of my invention is to provide a simple form of hinged construction whereby the chair back may be applied to the frame or removed therefrom in assembling or disassembling the chair. Further 25 objects of my invention will appear from a study of the specification and drawings, and will be particularly defined in the claims which terminate this specification.

Figure 1 is a section of the chair, taken 30 on a vertical plane extending from front to rear in which a portion of one arm is broken away in order to show the mechanism by which the back of the chair is controlled 35 and locked.

Fig. 2 is a vertical section taken on a plane substantially parallel with the back.

Fig. 3 is a side view of the corner broken away of the other arm of the chair from 40 that shown in Fig. 1, showing the spring by which the back of the chair is sustained, and its connection with the chair back.

Fig. 4 is a vertical section showing the locking lever.

Fig. 5 is a fragmentary section of the parts shown in Fig. 4, but upon a plane at right angles thereto.

Fig. 6 is a top view of the locking mechanism shown in Figs. 4 and 5.

The frame structure 1 of the chair may be 50 in the main of any suitable type of construction. The construction herein shown has arm boards 10 and beneath these, bars 11 which form a support for said boards.

This feature of construction is however, unnecessary excepting that there should be a portion of the frame at this point in which may be formed the grooves or channels in which the mechanism for supporting and controlling the back may be placed. 55

The back 2 may in general be of any suitable construction. It is pivoted at the point 21 upon the frame, and the portion thereof lying below the level of the arms 10 should be of such width as to enter between the 65 arms of the chair. This might however, be different if the hinges for the back were placed rearwardly of the rear posts 12 of the frame, and of the rear ends of the arms 10. The arm section of the frame at one side 70 is provided with a groove 15. This groove is preferably constructed in the bar 11 of the frame, or in its elevated member and is open at its top but is covered in the completed chair by the arm board 10. Within this 75 groove 15 is mounted a notched bar 3, which is connected by means of another bar 30 with the back of the chair at 32.

The notched bar 3 is preferably mounted in a trough-like member 31 composed of thin 80 sheet iron, bent so as to form a guide for notched bar 3, and to provide side flanges 33 by which it may be securely fixed in place. The trough 31 has a notch 34 which extends through both sides thereof from the 85 bottom edge, a distance of about half the depth of the trough. Within this is placed one end of a locking lever 35, of such size as to enter the notches of the bar 3 to thereby hold it against reciprocation within 90 the guide trough 31.

The locking lever 35 is pivoted at 36 upon an ear 37 of a small casting, which has a U shaped end 38 placed about the trough section at the point where the end of the lever 95 35 engages with the notched bar 3. The end 38 is preferably made in two parts, one at each side of the notch 34. A spring 39 which is mounted upon the same parts engages the lever 35 to hold it in locking position. These parts are mounted upon the part of the chair frame immediately below the arm 10, the end of the lever 35 projecting outwardly close under the arm 10. To unlock the back it is only necessary to pull 105 up on the lever 35.

The other arm member 11 is provided with a like slot 15, which may however, be

slightly different in its extent. Within this slot is mounted a spring by which the back is sustained, and by which it is brought into raised position after having been depressed. A spring 4 is a coil spring; its forward end is secured well toward the forward end of the arm, and preferably upon a bolt 40 which is secured to the arm 10. This spring is connected with a link 14 which extends through a slot 16 in the rear post of the chair and projects slightly into said slot. At this point it is provided with a hole 17 by which it may be attached to the chair back.

The manner in which I prefer to attach the chair back to the spring and to the locking mechanism is as follows:

A bar 42 passes horizontally through the bars 20, which form the main vertical members of the chair back. The ends of this bar extend outwardly into alignment with the links 30 and 14, extending respectively from the locking bar and the spring. Preferably the bar 42 is composed of a small pipe and is interiorly threaded at its ends to receive a threaded bolt 43. This construction is more clearly shown in Fig. 2.

The spring 4 should be under an initial strain or tension when the back is in its uppermost position, that is when the parts are in the position shown in Figs. 1 and 3. To facilitate the connection and disconnection of the back from the spring when in this position, it is necessary to prevent the spring from shortening beyond the position where it is under this desired initial tension, or otherwise the end of the link 14 would be drawn entirely within the slot 16, and it would be very difficult to properly connect the link 14 with the chair back. To secure this result I place a distention bar 41 within the spring, and have this bar of such length that it will keep the spring extended to the point which represents the desired initial tension. The ends of this bar might engage directly with the coils or the end eyes of the spring, or the forward end thereof may engage with the securing bolt 40. By this expedient the spring is held distended a sufficient amount to insure the projection of the link 14 enough to enable it to be secured to the back.

What I claim as my invention is:

1. In a chair, in combination, a frame, a back hinged thereto, the frame having a spring receiving slot in its arm section, and a spring in said slot and connected with the back to support it, and means for maintaining an initial tension upon the spring independent of the back.

2. In a chair, in combination, a frame, a back hinged thereto, the frame having a spring receiving slot in its arm section, and a spring in said slot and connected with the back to support it, and a bar within the

coils of said spring maintaining it under an initial tension.

3. The combination in a chair of a frame containing a side bar having a spring receiving groove in its upper edge opening rearwardly, an arm piece covering said groove, a coiled spring in said groove anchored at its forward end, means for connecting the rear end of said spring with the chair back, and means for maintaining the spring with an initial distention independent of its connections with the chair.

4. The combination in a chair of a frame containing a side bar having a spring receiving groove in its upper edge opening rearwardly, a fixed arm piece covering said groove, a coiled spring in said groove anchored at its forward end, means for connecting the rear end of said spring with the chair back, and a rod within said spring and engaging the spring at its ends, said rod being of a length to maintain the spring under an initial tension.

5. The combination with a chair having a frame and a hinged back, said frame containing a spring receiving recess opening rearwardly, a coiled spring within said recess having its forward end secured near the inner end of the recess, the ends of said spring being closed, a distending rod within the spring of a length to maintain the spring under an initial tension, and means for connecting the rear end of the spring to the hinged back.

6. The combination in a chair of a frame, a hinged back, the frame having a side member provided with a spring receiving recess extending from front to rear and opening rearwardly, a helical spring fitting said recess, means for securing the forward end of the spring, means for securing the rear end of the spring to the chair back, and a distending rod within said spring and maintaining an initial stretch in the spring which insures the projection from its containing recess of the means whereby it is secured to the chair back.

7. The combination with a chair frame and a hinged back, of a member secured to the frame and having a spring-receiving recess opening rearwardly, a coiled spring having its forward end secured in said recess, an attaching member secured to the rear end of the spring and extending rearwardly, and means carried by the spring for maintaining an initial tension on the spring sufficient to insure the projection of said attaching member from the rear end of the recess when said attaching member is detached from the back.

8. In a chair, in combination, a frame, a back hinged thereto, a guide member of sheet metal bent to form a U-shaped channel, a side member of said frame having a channel adapted to receive the channel portion of

said guide member, said channel having a transverse notch intersecting the bottom of the said channel, a reinforcing frame of U-shape embracing the guide channel at said notch, and having a similar transverse notch registering with said notch in the guide channel, a catch lever pivoted upon said re-

inforcing frame and adapted to enter said notches, and a notched bar mounted to reciprocate in the guide channel and being 10 connected with the back.

Signed at Tacoma, Washington, 25th this day of January 1916.

GEORGE W. SLYTER.
